(57) **CLAIM**

The ornamental design for a fishing tackle module, as shown and described.

DESCRIPTION

FIG. 1 is a first perspective view of a new and ornamental design for a fishing tackle module;

FIG. 2 is a front elevation view thereof;

FIG. 3 is a rear elevation view thereof;

FIG. 4 is a first side elevation view thereof;

FIG. 5 is a second side elevation view thereof;

FIG. 6 is a top plan view thereof;

FIG. 7 is a bottom plan view thereof; and,

FIG. 8 is a perspective view showing the fishing tackle module attached to the rim of a fishing bucket and holding fishing tackle.

The fishing bucket and fishing tackle are shown in phantom for environment only and form no part of the claimed design.
